UNITED STATES PATENT OFFICE.

JOHN H. JONES, OF FOSTORIA, OHIO.

CONCRETE OR CEMENT BUILDING-BLOCK.

SPECIFICATION forming part of Letters Patent No. 741,040, dated October 13, 1903.

Application filed April 1, 1903. Serial No. 150,526. (No model.)

To all whom it may concern:

Be it known that I, JOHN H. JONES, a citizen of the United States of America, and a resident of Fostoria, in the county of Seneca and State of Ohio, have invented certain new and useful Improvements in Concrete or Cement Building-Blocks, of which the following is a specification.

This invention relates to certain new and useful improvements in cement or concrete building-blocks of that character comprising an outer wall or shell and an inclosed space or chamber filled with some suitable material, such as cinders or cinders and sawdust or some analogous material; and it has for its objects, among others, to provide an improved building-block of this nature, with end depressions for hand-holes to facilitate the handling of the block, and also when the ends of two blocks are joined together the adjacent depressions form an inclosed hollow space permitting of the expansion and contraction by reason of changes of temperature, thus preventing cracking of the blocks. The preferred filling is such as to possess sufficient elasticity and absorptive qualities to prevent the core from dividing in case it becomes necessary to divide the block. For this purpose I employ a composition filling of cinders, sawdust, and granulated cork, with a sufficient amount of cement to hold the core together. The block is provided with an imitation rock-face, which may be given any desired color by coloring the material before it is molded.

Other objects and advantages of the invention will hereinafter appear, and the novel features thereof will be particularly pointed out in the appended claims.

The invention is clearly illustrated in the drawings, which, with the numerals of reference marked thereon, form a part of this specification, and in which—

Figure 1 represents a perspective view of a portion of a wall constructed of building-blocks in accordance with my invention. Fig. 2 is a perspective view of one of the blocks. Fig. 3 is a substantially central transverse section through the same. Fig. 4 is a substantially central longitudinal section through the same.

Like numerals of reference indicate like parts throughout the several views.

Referring now to the details of the drawings, 1 designates a block of the character above specified, 2 representing the walls of the shell or outer body; 3, the rock-face; 4, the core or filling, and 5 the depressions in the ends of the block. The shell or outer body is formed of concrete or cement, the thickness of the walls of which will be varied according to the use to which the block is to be put, the size of the same, and the strains to which it is to be subjected. The filling 4 may be of any suitable cheap material, such as cinders, granulated cork, or the like; but I preferably employ a composition of cinders, sawdust, and granulated cork, (or their equivalents,) together with a sufficient amount of cement to hold the core together, and I provide sufficient elasticity and absorptive qualities to yield slightly to the contractile action of the inclosing walls when the latter are subjected to the action of severe cold and yet aid in resisting the pressure and shocks to which the block is liable to be subjected. By this construction of filling the core is held together and practically to the walls of the outer body or shell, so that in case it becomes necessary to divide the block the core is held against dividing and from separation from the walls of the shell.

The depressions 5 in the ends of the block serve a double function. They provide convenient means for handling the block, whereby one person can move the same as may be required, and when the blocks are arranged end to end these depressions come opposite each other and form an inclosed hollow space, providing for the contraction and expansion without cracking of the block.

As will be evident from Fig. 1, the end blocks of the structure are provided upon both a side and end with the rock-facing 3 for purposes which it is not necessary to explain.

The block is formed by molding, the process of which it is not thought necessary to herein describe.

What I claim as new is—

1. As an improved article of manufacture, a building-block formed with a shell of concrete with an interior chamber or space, a fill-

ing of cinders, sawdust, granulated cork and cement compounded and made homogeneous, substantially as described.

2. As an improved article of manufacture,
5 a building-block formed with a shell of concrete with an interior chamber or space, and a filling of cinders, sawdust, granulated cork and cement compounded and made homogeneous, the ends of the block being formed
10 with hand-holes in the outer wall only, as and for the purpose specified.
3. A wall formed of composite blocks with

hand-holes in the ends of the outer wall only, said blocks being arranged with the adjacent hand-holes opposed to each other whereby 15 they form inclosed dead-air spaces, as and for the purpose specified.

Signed by me at Fostoria, Ohio, this 28th day of March, 1903.

JOHN H. JONES.
